UNITED STATES PATENT OFFICE.

FREDERICK J. SCHMITT, OF PETOSKEY, MICHIGAN.

DESIGN FOR A SCRAPER.

50,078.

Specification for Design.

Patented Dec. 19, 1916.

Application filed August 12, 1916. Serial No. 114,647. Term of patent 14 years.

To all whom it may concern:

Be it known that I, FREDERICK J. SCHMITT, a citizen of the United States, residing at Petoskey, in the county of Emmett and State of Michigan, have invented a new, original, and ornamental Design for a Scraper, of which the following is a specification, reference being had to the accompanying drawing, forming a part thereof.

The figure is a perspective view of a scraper, illustrating my new design.

I claim:

The ornamental design for a scraper, as shown.

In testimony whereof, I affix my signature.

FREDERICK J. SCHMITT.
